UNITED STATES PATENT OFFICE

111,323

DESIGN FOR A CLOSURE FASTENER

Albert J. Komenak, Stamford, Conn., assignor
to The Excelsior Hardware Company, Stam-
ford, Conn., a corporation of Connecticut

Application August 6, 1936, Serial No. 64,280

Term of patent 7 years

To all whom it may concern:

Be it known that I, Albert J. Komenak, a citizen of the United States, residing at Stamford, in the county of Fairfield and State of Connecticut, have invented a new, original, and ornamental Design for a Closure Fastener, of which the following is a specification, reference being had to the accompanying drawing, forming part thereof.

Figure 1 is a front view, Figure 2 is a perspective view, Figure 3 is a side view, Figure 4 is a top plan view, and Figure 5 is a bottom plan

view of a closure fastener showing my new design.

The characteristic feature of the design resides in a handle of horn-like shape extending in general alignment with an elongated fastening body and somewhat forwardly thereof at one end of said body.

I claim:

The ornamental design for a closure fastener, substantially as shown and described.

ALBERT J. KOMENAK.
